(57) CLAIM

The ornamental design for a personal care product container, as shown and described.

DESCRIPTION

FIG. 1 is a perspective view of the personal care product container;

FIG. 2 is a right side view, the left side being a mirror image thereof;

FIG. 3 is a front view thereof;

FIG. 4 is a rear view thereof;

FIG. 5 is a top view thereof;

FIG. 6 is a bottom view thereof; and,

FIG. 7 is a perspective view of the personal care product container in an opened position.

FIGS. 1-2 and 7 show portions of the personal care product container in broken lines. The portions shown in broken lines form no part of the claimed design.
